Andrew Little by A. L. D. D. D. a. a.

UNITED STATES PATENT OFFICE.

ANDREW LITTLE, OF NEW YORK, N. Y.

DESIGN FOR A FONT OF PRINTING-TYPE.

SPECIFICATION forming part of Design No. 16,484, dated January 19, 1886.

Application filed November 12, 1885. Serial No. 182,648. Term of patent 3½ years.

To all whom it may concern:

Be it known that I, ANDREW LITTLE, of the city, county, and State of New York, have invented and produced a new and original Design for a Font of Printing-Type, of which the following is a specification.

The nature of my design is clearly shown in the accompanying typographic impression, to which reference is made; and it consists of 10 a letter of the semi-Gothic character shaded upon the right and below by a light line following the configuration of the letter. The up-and down portion of the A, D, E, F, H, M, N, T, and Y is ornamented upon the left, at 15 its base, by the short line gradually narrowed, and this ornamentation is found in the upper right-hand termination of the C, S, V, and W, in the lower right-hand termination of the G, and the upper termination of the J. In the 20 H the upper right-hand termination is of similar character, extending to the right. In the P this termination, extended to the right, is found at the base of the up-and-down portion, and in the Q the tail of the letter shows 25 a similar termination, while the lower right-hand termination of the R shows the ornamentation extending to the left. The A, F, H, K, M, N, P, T, and Y are extended below the line.

30 In the numerals the character of the design is preserved, notably in the 1, 2, 3, 4, 6, and 7, in the symbol "&," the dollar and pound-sterling marks, and in the punctuation-marks, more particularly in the interrogation-mark.

35 This design differs from the type patented by J. M. Conner, No. 9,582, October 10, 1876, in that, while in that example a letter shaded upon the right and below is shown, no one of

the letters is provided with the short line gradually narrowed, and that none of the letters 40 are extended below the line; and from the patent granted Jackson, April 13, 1883, No. 13,834, which shows a letter shaded upon the right and below by a series of light inclined lines, but which letters are not provided with the short 45 line gradually narrowed.

Having now set forth my invention, I claim as new—

The design for a font of printing-type, as herein shown and described, the same consisting of a letter of the semi-Gothic character shaded upon the right and below by a light line following the configuration of the letter, the up-and-down termination of the A, B, E, F, H, L, M, N, T, and Y ornamented upon the 50 left, at its base, by the short line gradually narrowed, and this ornamentation formed in the upper right-hand termination of the C, S, V, and W, in the lower right hand termination of the G, and the upper termination of the J, 55 in the H the upper right-hand termination of similar character extended to the left, in the P this termination extended to the right at the base of the up-and-down portion, the tail of the Q ornamented by it, the lower right-hand termination of the R ornamented by it, 60 extended to the left, the A, F, H, K, M, N, P, T, and Y extended below the line, and the character of the design preserved in the numerals, symbol "&," dollar and pound-sterling marks, 65 and in the punctuation marks.

ANDREW LITTLE.

In presence of—

WILLIAM V. H. HICKS,
A. SIDNEY DOANE.
